UNITED STATES PATENT OFFICE.

FRANK A. ZIKA, OF CHICAGO, ILLINOIS, ASSIGNOR OF ONE-HALF TO JAMES E. BARRY,
OF CHICAGO, ILLINOIS.

SYSTEM OF ELECTRICAL DISTRIBUTION.

1,133,525.

Specification of Letters Patent. Patented Mar. 30, 1915.

Application filed June 22, 1914. Serial No. 846,441.

To all whom it may concern:

Be it known that I, FRANK A. ZIKA, a subject of Austria-Hungary, and resident of Chicago, in the county of Cook and State of Illinois, have invented certain new and useful Improvements in Systems of Electrical Distribution, (Case D,) of which the following is a full, clear, and exact specification.

10 My invention relates to improvements in high potential circuits for the electric spark producing means for internal combustion engines and means for controlling said circuits.

15 One of the objects of my invention is to provide means for controlling the high potential circuits coming from two sources of current supply for a dual set of spark plugs for each of the cylinders of an internal combustion engine, whereby either source of current supply may instantly be connected to either set of spark plugs or both sources of current supply may be connected to the respective set of spark plugs by a simple and 20 easily operable switch and whereby all wires and connections for the entire number of spark plugs may immediately and simultaneously be removed, in a self contained structure, from said plugs.

25 30 Another object of my invention is to provide a housing or protecting cover for the spark plugs, comprising an integral structure, such as a continuous tube adapted to cover a plurality of plugs and which can be bodily removed from the engine for inspection, cleansing and to permit removal and replacement of one or more of said plugs.

35 40 Other and further objects of my invention will become readily apparent to persons skilled in the art from a consideration of the following description when taken in conjunction with the drawings which are a part hereof and in which—

45 Figure 1 represents an elevation of an engine showing my invention applied thereto. Fig. 2 is a longitudinal section taken on line 2—2 of Fig. 1. Fig. 3 is a section taken on line 3—3 of Fig. 2. Fig. 4 is a transverse section taken on line 4—4 of Fig. 1. Fig. 5 is a central sectional view of the switch mechanism. Fig. 6 is a transverse section taken through the switch on line 6—6 looking in the direction of the arrows. Fig. 7 is a similar section taken on line 7—7 of Fig. 5; looking in the direction of the arrows.

Fig. 8 is a similar section taken on line 8—8 of Fig. 5, looking in the direction of the arrows, and Fig. 9 is a top plan view of the removable member or cover of a switch, and Fig. 10 is an enlarged detail section taken on the line 10—10 of Fig. 1.

In all the views the same reference characters are employed to indicate similar parts.

15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

end of the spark plugs A and B. Wires a^1 , a^2 , a^3 , and a^4 connect the respective plugs A that are supported in the partition 34 with the magneto 21, and wires b^1 , b^2 , b^3 , b^4 , b^5 , connect the respective plugs B with wires leading from the secondary of the induction coils contained in the casing 23. Other wires m^1 , m^2 , m^3 , and m^4 lead from the magneto 21 to a suitable switch contained in the casing 23. Wires d^1 , d^2 , d^3 and d^4 connect the said switch with the distributor 25, and wires 22^a and 22^b connect the storage battery 22 with the primary of the induction coils contained within the casing 23. By this means the spark plugs A of the respective cylinders 17, 18, 19 and 20, may be energized by sparks coming from the magneto 21 and spark plugs designated by the letter B may be energized by current coming from the induction coils, located within the casing 23. These wires are contained for purpose of convenience, within fixed protecting pipes 41, 42, and 43. Pipe 43 terminates in a switch 44. These pipes are fixed to the engine structure by clips 45, or otherwise. The lower member, 46 of the switch 44, is secured to the upper end of the pipe 43, and the upper or top member 47 of the switch, is secured to a pipe 48, which is secured to the protecting pipe or tube 27, as at 49. The arrangement is such that when the tube or pipe 27 is removed the pipe 48 and the upper cap member 47 of the switch 44, as well as the wires connecting these instrumentalities may be bodily removed with the tube.

The switch 44 is preferably made of hard rubber and contains five major parts, the base 46, the cap 47, and the cup part 50, which contains a movable ring 51, and an internal rotatable disk 52. The latter rotates upon a central stem 53. The ring 51 is adapted to be slightly oscillated by means of the radially extending handle 54, which is secured thereto, and the disk 52 is adapted to be slightly oscillated by the radially disposed handle 55, which is secured to the said disk. These parts are limited in their movements in slots 56 and 57 respectively, which are made in the side walls of the cup shaped member 50. The ring 51 carries contact pins A^1 , A^2 , A^3 , and A^4 which are adapted to complete the circuit for the spark plugs indicated by the letter A and the disk 52 carries similar pins designated by the letters B^1 , B^2 , B^3 and B^4 which are adapted to complete the electric circuits for the respective spark plugs B. These pins are circumferentially elongated on the under side of the disk as at A^6 , A^7 , A^8 and A^9 so as to maintain electric circuit with the respective pins immediately underlying the rings 51, when the said rings are slightly oscillated, and the disk 52 is provided with similar elongations B^6 , B^7 , B^8 and B^9 , respectively.

The cup shaped member 50 contains similar contact pins without extensions which I have indicated by the same reference numerals A^2 , A^3 , A^4 , and A^5 , and B^2 , B^3 , B^4 and B^5 , respectively.

The cover or top member 47, shown reduced in size in Fig. 9, is provided with 16 perforations and an equal number of contacting pins, four of which pins I have designated by reference characters A^2 , A^3 , A^4 and A^5 , and the other complementary pins I have designated by reference characters A^{10} , A^{11} , A^{12} and A^{13} . The other set of pins I have designated by the reference characters B^2 , B^3 , B^4 and B^5 and the complementary pins by B^{10} , B^{11} , B^{12} and B^{13} . A^2 and B^{13} are connected together by a cross piece and from this cross piece the wire a^7 is connected, and this wire communicates with the spark plug A of cylinder 17, and in like manner the respective connections for the other pins are made on top of the cover, as clearly indicated in Fig. 9.

A switch lever 60 is pivoted, as at 61, and is connected at its ends by rods 62 and 63, respectively. The rod 63 is pivotally connected with the switch lever 54 which oscillates the disk 52 and the rod 62 is connected with the lever 55 which oscillates the ring 51, so that when pressure is applied to either end of the switch lever 60, as in the operation of a push button switch, the levers 54 and 55 will be respectively oscillated, one will be moved ahead and the other lever will be moved in a rearward direction. Now it is evident that if the disk 52 be rotated slightly in one direction, by means of the push button switch referred to, that the current will be communicated from the magneto to the series of spark plugs A, for instance, and if the ring 51 be at the same time slightly oscillated in the opposite direction, current will be carried from the induction coils, energized by the storage battery, to the series of spark plugs B and if the ring and disk be oscillated in the opposite direction, as by pressure upon the other end of the switch lever 60, the respective spark plugs will be energized from the other source of electric energy so that by merely pressing on one or the other end of the switch lever 60 the series of spark plugs may be energized by either source of electric energy, the battery or the magneto, or from both sources of energy, or by pressing the switch lever only slightly in one direction or the other, either set of spark plugs may be energized by either source of electric energy.

Wires d^1 , d^2 , d^3 , and d^4 lead from the switch casing 23 to a distributor 25, the rotating member of the distributor being "grounded" to the frame of the engine, the circuit will be substantially as follows: over one wire from the magneto to a spark plug, and from the spark plug to a

"ground" on the engine frame and from that ground to the rotating member of the distributor 25 and through the wire selected by the distributor d^1 , d^2 , d^3 , and d^4 , as the case may be, back to the magneto, over one of the wires m^1 , m^2 , m^3 , or m^4 , and in this manner the circuit may also be closed and traced from the secondary windings of the induction coils contained within the casing 38, through any one of the respective spark plugs.

As the tube 27, and the tube 48 are secured together and contain the wires necessary for completing the circuits to the spark plugs, and as the tube 48 is also secured to the bodily removable cap member 47, of the switch, it is only necessary to loosen the thumb screws 30—30 from the stems or rods 31—31 in order that the conductors contained within 20 in the tubes 27 and 48 may be entirely taken away and the spark plugs examined, removed or changed, and when necessary a new structure of the same character may replace the one removed.

25 While I have herein shown a single embodiment of my invention and certain arbitrary arrangement of circuits for the purpose of clear disclosure, it is manifest that changes may be made both in the arrangement 30 of the circuits and the character of the parts, without departing from the spirit of my invention or the scope of the appended claims.

Having described my invention, what I 35 claim is:—

1. In a system of the character described, the combination of two sources of electric energy; a set of spark plugs to be energized by either source; permanent electric circuits connecting said sources of current to a switch; a switch, having a removable member; a removable, conductor-carrying structure connected to the removable member of said switch, and conductors carried by said 40 structure to connect the respective spark plugs to the switch and means for securing the said structure in place.

2. In a system of the character described, the combination of two sources of electric 50 energy; a set of spark plugs to be energized by either source; permanent electric circuits connecting said source of current to a switch; a switch, having a removable member; a removable, conductor-carrying structure, carrying the removable member of said switch; conductors carried by said structure to connect the respective spark plugs to the switch; yielding terminals for each said conductor carried by said structure to automatically effect such connections and means 55 for securing said structure in place with reference to said plug.

3. In a system of the character described, the combination of two sources of electric 60 energy; a set of spark plugs to be energized

by either source; permanent electric circuits connecting said sources of current to a switch; a switch having a removable member; a removable conductor carrying tube perforated at intervals to admit said spark 70 plugs and carrying said switch member; a longitudinally extending partition in said tube, above said perforation; conductors carried by said tubes, above said partition, to connect the respective spark plugs to the 75 switch; yielding terminals, one for each said conductor, secured in said partition, to automatically effect such connection and means for securing said structure in place with reference to said plugs. 80

4. In a system of the character described, the combination of two sources of electric energy; two sets of spark plugs; permanent electric circuits connecting said sources of current to a switch; a switch, having a removable member; a removable, conductor-carrying structure mechanically connected with a removable member of the switch; conductors carried by said structure to connect respective spark plugs to the switch 85 and means for securing said structure in place. 90

5. In a system of the character described, the combination of two sources of electric energy; two sets of spark plugs; exposed 95 terminals on the outer ends of said plugs; permanent electric circuits connecting said sources of energy to a switch; a switch, having a removable member; a removable conductor-carrying structure mechanically connected to a removable member of the switch; conductors carried by said structure; spring clips secured to the terminals of said conductor to connect respective spark plugs to the switch and means for securing said 100 structure in place. 105

6. In a system of the character described, a separable conductor-carrying tube, perforated at intervals to receive spark plugs; a longitudinally extending partition of insulating material, in said tube; plugs, carrying spring clips for engaging spark plugs, supported by said partition and registering with said perforations; conductors connected with said plugs, one with each; another 110 tube connected with said first tube, through which said conductors pass; a switch, one member of which is removable with said tube structure and means for separably securing said structure to an engine. 115

7. In a system of the character described, a separable conductor-carrying tube, perforated at intervals to receive spark plugs; a longitudinally extending partition of insulating material, in said tube; plugs, carrying spring clips, for engaging spark plugs, supported by said partition and registering with said perforations; conductors connected with said plugs, one with each; another 125 tube connected with said first tube, through 130

which said conductors pass; a switch, one member of which is removable with said tube structure; means for separably securing said structure to an engine; two sources of electric energy and suitable electric circuits connecting said switch thereto, whereby to control said sources of energy.

8. A housing for a plurality of spark plugs comprising a tube having its side wall perforated at suitable intervals corresponding to the distance of separation of said plugs; a partition extending longitudinally of said tube; a series of contact members, for connection with said plugs, projecting from said partitions and registering with the respective perforations and a series of conducting wires, one connected to each contact member, within the tube between the partition and the closed side wall of the tube.
9. A housing for a plurality of spark plugs comprising a tube having its side wall perforated at suitable intervals corresponding to the distance of separation of said plugs; a partition extending longitudinally

of said tube; a series of contact members, for connection with said plugs, projecting from said partitions and registering with the respective perforations; spring clips secured to the outer ends of said contact members, for engagement with said plugs.

10. A removable spark plug protector and connector comprising a tube of insulating material provided with alining perforations; a substantially diametric, longitudinally extending partition; a plurality of contact members extending below said partition registering with said perforations and conducting wires within the tube, above the partition connected to the respective members and means to detachably secure the tube to an engine.

In witness whereof, I have hereunto set my hand and affixed my seal, this 18th day of June, A. D. 1914.

FRANK A. ZIKA. [L.S.]
